METALLIC BUILDING CONSTRUCTION

Henry Jentzer, St. Louis, Mo.

Application June 9, 1939, Serial No. 278,272

3 Claims. (Cl. 189—88)

My invention has relation to improvements in metallic building construction and consists of the novel features more fully hereinafter described in the specification and pointed out in the claims.

The invention is directed primarily to the wall construction of buildings, the respective elements of which, studding, sheathing, etc., are of metal with effective insulation between the outside and inside surfaces of the wall, all of which elements have been prefabricated so that on the site of the building erection is the only construction required.

The primary object of the invention is to provide a fireproof building construction at comparatively low cost and that does not necessarily require the services of skilled mechanics.

A further object of the invention is to provide interrelated parts that are adapted for rapid assembly into a strong, durable building.

Other advantages inherent in my improved building construction will be better apparent from a detailed description thereof in connection with the accompanying drawings, in which:

Figure 1 is a side elevation of a finished building embodying my improved construction; Fig. 2 is a side elevation of the same building before the sheathing has been put in place; Fig. 3 is an enlarged horizontal cross-section taken through a corner of the building on the line 3—3 of Fig. 1; Fig. 4 is an enlarged horizontal cross-sectional detail taken on the line 4—4 of Fig. 1; Fig. 5 is a vertical cross-sectional detail taken on the line 5—5 of Fig. 1; Fig. 6 is a horizontal section through the corner of the building similar to that shown in Fig. 3 except that it is considerably enlarged; Fig. 7 is a vertical cross-sectional detail taken on the line 7—7 of Fig. 1 with parts broken away and on the same scale as Fig. 6; Fig. 8 is a vertical cross-sectional detail taken on the line 8—8 of Fig. 1 and on the same scale as Figs. 6 and 7; Fig. 9 is a greatly enlarged vertical cross-sectional detail taken on the line 9—9 of Fig. 2; and Fig. 10 is a fragmentary perspective view of a special shape of strip for retaining the sheathing in place.

Referring to the drawings, B represents a building of conventional design embodying my improved construction wherein studding members 1, 1', etc. rest upon a shoulder 2 formed in the concrete foundation 3. These members are secured to the portion of the foundation 3 above the shoulder 2 by means of lag screws 4, 4' or equivalent devices. In the present instance the studding members 1 are Z-shaped in cross-section (al-

though this shape may be varied if desired) and are spaced approximately 16" on center according to the usual practice.

By referring to Fig. 3 it will be observed that there is no studding 1 at the corner of the building, but instead the member 1' forming a part of side wall w and the member 1'' forming a part of end wall w' are set back a short distance for the purpose of forming a rounded corner on the building in a manner presently to be described.

The studding members 1, 1', 1'' preferably extend to the height of a story and have a structural member 5 extending across their upper ends and secured to them in any desirable manner, said member 5 serving as a plate on which the roof R of the building is carried. The specific construction of the roof does not form a part of the present invention and will not be further described.

20 Specially formed metallic strips 6 (Fig. 10) extend transversely across the studding member 1 in uniformly spaced relation and are secured to the outer flange 7 of each of the studding members 1. The strips 6 are bent from sheet metal in such form as to provide a flange element 8, a seat member 9 transversely to the flange member, a slot 10 and a flanged portion 11 having a double bend so as to provide a slot 12. The flange 8 of the strip is provided with a number of holes 13 arranged in pairs as shown, whereby the strip is bolted by means of bolts 14 to each of the studding members 1. The strips are positioned on the studding members with the open side of slot 10 at the top of the strip and the open side of slot 12 at the bottom for receiving the bottom edge of one section of sheathing and the top edge of the next adjacent section of sheathing.

Each section or sheet of sheathing 15 is offset slightly so as to provide a shoulder 16 adjacent to the upper edge of the sheet (with respect to the manner in which the sheet is placed on the building) and is also off-set so as to provide a ledge 17 and a downwardly extending tongue 18 at the lower edge of the sheet. As shown in Fig. 45 the special strips 6 serve to hold the respective sheets 15 of the sheathing in place without the use of rivets or bolts or other securing devices since each sheet 15 has its tongue 18 resting in slot 10 of strip 6, the sheet being carried by means of its offset 17 on the seat 9 of the strip and having its upper edge nested in slot 12 formed in the flange 11 of the strip.

At the corners of the building (Figs. 3 and 6) there are arcuate strips 19 bolted to the end studding members 1', 1'' and articulating with strips

6 of wall w and wall w' so as in effect to form a continuation thereof. The strips 19 are of the same cross-sectional shape as the strips 6 and receive arcuate sheets of sheathing 20 in the same manner as the sheets 15 are held by upper and lower strips 6.

In order to avoid the conduction of heat or cold from the outside of walls w and w' to the inside thereof, suitable heat insulating material 21 is interposed between flange 7 of studding member 1 and flange 8 of strip 6. The adjacent vertical edges of sheets 15, 15 are held together by what may be termed a sealing strip 22 which is formed (Fig. 6) so as to present open slots 23, 23 outwardly to receive the sheets 15, 15.

Suitable metal lath 24 is secured in any desirable manner to inner flange 7' of the studding members 1, 1', 1'', etc. over which plaster is laid according to the usual practice. Suitable insulating material 25 is packed within the space between the sheathing 15 and the metallic lath 24.

Fig. 2 shows a framed opening 0 in which is secured a metallic casement window 26. The frame 27 of the window is provided with an outer flange 28 around the entire margin of which is a slot 29 to receive the adjacent edges of the sheathing 15. The construction of the window will not be described in detail as it forms the subject matter of a separate application filed on even date herewith.

Having described my invention, I claim:

1. A sheathing retaining strip comprising a base flange, a seat member adjacent thereto, said base flange and seat being formed to provide a slot therebetween, said slot opening upwardly and coextensive with the base flange, and a flange projecting downwardly from said seat in

spaced relation with and overlying the base flange, said latter flange having a slot formed therein, the last mentioned slot opening downwardly, being parallel with the first slot, and coextensive with the base flange.

2. A sheathing retaining strip bent from sheet metal to provide a base flange, a seat bent outwardly from the base flange to provide a slot therebetween, said slot opening upwardly and coextensive with the base flange, and a retaining flange bent downwardly from the seat and formed to provide a slot coextensive with the base flange, open oppositely to, parallel with, and overlying the first mentioned slot.

3. In a building construction, the combination of metallic sheathing plates and horizontally disposed retaining strips therefor, each strip having a base flange, a seat element projected upwardly and forwardly therefrom to form a slot between base flange and seat, said slot being coextensive with the flange and the seat and open upwardly, each strip also having a securing flange extending downwardly from the seat in spaced relation with the base flange, said securing flange having a slot formed in it opening downwardly coextensive with the base flange and parallel with and overlying the first slot, said plates each having a ledge resting on the aforesaid seat and a tongue extending downwardly from said ledge disposed in the upwardly open slot, and said plates each having an upwardly extending tongue slightly offset with relation to the balance of the plate, said tongue being disposed in the slot of the securing flange, whereby the strips and the plates collectively form a substantially plane surface.

HENRY JENTZER.
